CLAIM

The ornamental design for an oral cavity image acquisition device, as shown and described.

DESCRIPTION

1. Oral cavity image acquisition device.

1.1 is a front view of an oral cavity image acquisition device;

1.2 is a back side view thereof;

1.3 is a top side view thereof;

1.4 is a bottom view thereof;

1.5 is a front perspective view thereof;

1.6 is a back perspective thereof; and

1.7 is a side view thereof.

The portions of the oral cavity image acquisition device shown in broken lines form no part of the claimed design.
